United States Patent Office.

FRED HEALD, OF PHILADELPHIA, PENNSYLVANIA, ASSIGNOR TO McCALLUM, CREASE & SLOAN, OF SAME PLACE.

Design No. 4,314, dated August 30, 1870.

DESIGN FOR A CARPET PATTERN.

The Schedule referred to in these Letters Patent and making part of the same.

ALFRED HEALD, of Philadelphia, county of delphia, State of Pennsylvania, have invented duced a new and original Design for a Carpet rn, of which the following is a specification.
e figure in the accompanying drawing represents ent of a carpet pattern to illustrate my design, consists of a series of ornamental stripes, A, rnamental diagonal stripes B, together with ornaments, all too clearly shown in the drawing d minute explanation.
spective of the colors employed,

I claim—
The design for a carpet-pattern, substantially as described, and as illustrated in and by the accompanying drawing.

In testimony whereof I have signed my name to this specification in the presence of two subscribing witnesses.

ALFRED HEALD.
